PREFABRICATED BUILDING

Austin T. Levy, Harrisville, R. I.

Application November 1, 1937, Serial No. 172,211

13 Claims.

(Cl. 72—1)

My invention relates to prefabricated buildings.

It has heretofore been proposed to heat insulate and eliminate condensation on the inner walls, of such houses of the type having a metallic 5 through connected wall frame, and having wall panels in said frame covered by a cementitious material on opposite wall faces, by covering the surfaces of the through connected metal parts with insulating material such, for example, as compressible and absorbent felt or the like disposed between the metal frame and the anchoring means for the cementitious material. However, I have found that absorbent and compressible insulating material does not maintain its good heat insulating 10 qualities uniformly under all conditions, and tests have shown definite losses of these qualities when such material is wet or severely compressed or when punctured by abrasion.

My invention has among its objects to provide 15 improved means for heat insulating such buildings, and, more particularly, such improved means especially adapted to use with such insulating materials. A further object of my invention is to provide improved means for maintaining the felt, or other insulating material, dry, while also maintaining the same free from severe compression or punctures by abrasion. A still further object of my invention is to provide such improved means adapted to be readily and inexpensively embodied 20 in the wall structure in the process of erection, and whereby, while effectively insulating the wall and removing any danger of condensation on the inside walls, I am also able to maintain the insulating material in good heat insulating 25 condition for an indefinite period after the walls have been coated with cementitious material. These and other objects and advantages of my improved construction will, however, hereinafter more fully appear.

40 In the accompanying drawing, I have shown for purposes of illustration, three embodiments 45 which my invention may assume in practice.

In the drawing—

Figure 1 is a perspective view of a portion of a 50 wall equipped with one form of my improvement, the outer cementitious material being broken away at the top to facilitate illustration;

Fig. 2 is a perspective sectional view showing 55 this form of my invention applied to an intermediate stud;

Fig. 3 is a similar view showing the same applied to a corner stud;

Fig. 4 is a transverse sectional view showing 60 a modified form of the invention applied to an intermediate stud, and

Fig. 5 is a like view of a further modified construction.

In the illustrative construction shown in Figures 1 to 3, the wall, as heretofore, includes a bottom channel sill 1 carried on a suitable foundation 2 and also a top channel plate 3, the edges of panels 4 of fibrous heat insulating material, herein carrying suitable anchoring material spacing rods 5, being received in the channels 1 and 3 and in intermediate channel studs 6 and corner channel 10 studs 7 in a well known manner; the through connected metal frame members 1, 3, 6 and 7 being covered on their opposite faces with insulating material in the form of strips 8 of felt or the like, disposed between opposite faces of these metal 15 members and the anchoring material, herein reticulated wire or mesh 9 spaced by the rods 5 and acting to clinch the stucco 10 and plaster 11 to the opposite faces of the walls.

In this form of my improved construction, I 20 provide over each outer felt strip 8, a protecting coating adapted to prevent the entry of water and also to resist compression or abrasion of the underlying felt. Herein, this coating is in the form of a slightly wider strip 12 of paper, an ordinary 25 waterproof building paper of heavy character being preferred, this paper being attached in a suitable manner as by tacking it to the panel or by adhesively connecting it thereto or to the felt. However, it will be understood that if desired I may 30 use a coating of so-called aluminum foil or like equivalent insulating material applied directly to the felt, or so-called metallization on paper, attached as above described. In practice, however, it is found that the results obtainable with the 35 ordinary building paper described, are such as to make unwarranted the additional expensive involved in such foil or other special coatings or coverings. As shown in Figure 5, it will also be noted that I may, under certain conditions, where 40 desired, also provide an additional strip 13, corresponding to the strip 12, but similarly located over the inside felt strips 8, although in practice, it is here also found that the results obtained by using a single outside strip are such as ordinarily 45 to make the use of such an inside strip unnecessary. In Figure 4, I have also illustrated a further modified construction wherein a single strip is used, this strip being similarly located on the inside, but such a construction is similarly not pre- 50 ferred.

As a result of my improved construction, with all of the through connected metal parts thus covered by felt and coated or covered in my improved manner, it is found that markedly improved and 55

more uniform results are obtained. More particularly, the additional insulating strip formed by the waterproof heavy paper, acts to prevent the underlying felt 8 from being wet by the cementitious material, while the paper continues to perform this function not only during, but after, the cementitious coatings are applied, in such manner as thus effectively to prevent the loss of maximum heat insulating qualities of the felt. At the same time, the heavy paper strips also act to minimize compression of the felt strips, while also acting effectually to prevent the puncturing of the felt by compression. As a result, the life of the felt insulating strips is substantially extended, at the same time that the heat insulating qualities thereof are maintained. Further, it will be evident that where foil is used, the latter will also increase the heat insulating quality of the wall, although with ordinary building paper, it is found that the heat loss is so low as to be negligible.

While I have in this application specifically described three embodiments which my invention may assume in practice, it will be understood that the same have been shown for purposes of illustration, and that the invention may be modified and embodied in various other forms without departing from its spirit or the scope of the appended claims.

What I claim as new and desire to secure by Letters Patent is:

- 30 1. In a building, a marginal metal wall frame presenting a panel aperture, a panel in said aperture, anchoring means for a cementitious coating over said frame and panel, insulating means for said frame, and protecting means for said insulating means between the latter and the cementitious coating.
- 40 2. In a building, a marginal metal wall frame presenting a panel aperture, a panel in said aperture, anchoring means for a cementitious coating over said frame and panel, insulating means for said frame, and protecting means for said insulating means between the latter and the cementitious coating comprising a waterproof coating.
- 45 3. In a building, a marginal metal wall frame presenting a panel aperture, a panel in said aperture, anchoring means for a cementitious coating over said frame and panel, insulating means for said frame, and protecting means for said insulating means between the latter and the cementitious coating comprising a waterproof coating having a sufficient body to reduce compression or abrasion.
- 55 4. In a building, a marginal metal wall frame presenting a panel aperture, a panel in said aperture, anchoring means for a cementitious coating over said frame and panel, insulating means for said frame disposed beneath said anchoring means, and protecting means for said insulating means between the latter and said anchoring means.
- 65 5. In a building, a marginal metal wall frame presenting a panel aperture, a panel in said aperture, anchoring means for a cementitious coating over said frame and panel, absorbent insulating means for said frame, and means for preventing wetting of said insulating means by the cementitious coatings and disposed between said anchoring and insulating means.
- 70 6. In a building, a marginal metal wall frame presenting a panel aperture, a panel in said aperture, anchoring means for a cementitious coat-

ing over said frame and panel, compressible insulating means for said frame, and means for protecting said insulating means from compression and disposed between said anchoring and insulating means.

7. In a building, a marginal metal wall frame presenting a panel aperture, a panel in said aperture, anchoring means for a cementitious coating over said frame and panel, insulating strips for said frame beneath said anchoring means, and protecting strips for said insulating means between the cementitious coating and said insulating strips.

8. In a building, a marginal metal wall frame having through connections to opposite faces thereof, a panel positioned with respect thereto, anchoring means for a cementitious coating over said frame and panel, insulating strips for said frame disposed beneath said anchoring means, and waterproof protecting strips for said insulating means and disposed between the latter and said anchoring means.

9. In a building, a marginal metal wall frame having through connections to opposite wall faces and presenting a panel aperture, a panel in said aperture, anchoring means for a cementitious coating over said frame and panel, insulating strips for said frame, and strips of paper overlying said insulating means beneath said anchoring means.

10. In a building, a marginal metal wall frame having through connections to opposite wall faces and presenting a panel aperture, a panel in said aperture, anchoring means for a cementitious coating over said frame and panel, insulating strips for said frame, and strips of heavy waterproof paper overlying said insulating strips beneath said anchoring means.

11. In a building, a marginal metal wall frame having through connections to opposite wall faces and presenting a panel aperture, a panel in said aperture carrying anchoring means for a cementitious coating, insulating strips for said frame, and coating means overlying said insulating strips beneath said anchoring means, said anchoring means and insulating strips being on each of the faces of said wall frame, and said coating means overlying the insulating strips on the outer face of said frame.

12. In a building, a marginal metal wall frame having through connections to opposite wall faces and presenting a panel aperture, a panel in said aperture carrying anchoring means for a cementitious coating, insulating strips for said frame, and coating means overlying said insulating strips beneath said anchoring means, said anchoring means and insulating strips being on each of the faces of said wall frame, and said coating means overlying the insulating strips on the inner face of said frame.

13. In a building, a marginal metal wall frame having through connections to opposite wall faces and presenting a panel aperture, a panel in said aperture carrying anchoring means for a cementitious coating, insulating strips for said frame, and coating means overlying said insulating strips beneath said anchoring means, said anchoring means and insulating strips being on each of the faces of said wall frame, and said coating means overlying the insulating strips on the inner and outer faces of said frame.
